METHOD OF MAKING LUGGAGE FRAMEWORK

John Riess, St. Louis, Mo., assignor to Henry Hotze & Sons Company, a corporation of Missouri

Application August 18, 1944, Serial No. 550,102

5 Claims. (Cl. 154—2)

This invention relates to a new method of making luggage frame work for hand carried luggage or bags, from flexible materials such as leather, to which the sections or sides of the luggage are attached and in fact it may be stated that the invention herein disclosed, goes to the method of constructing luggage, for when the method of making the frame work thereof is carried out with the attached sides or sections, there but remains the completion of attaching the base or bottom of the luggage.

The purpose of the invention therefore, is to eliminate the application and use of metal frames for hand carried luggage and to build up a frame structure of flexible materials, from which the luggage sides are extended and which will retain its preformed shape during use of the luggage.

A further object is to provide a luggage frame of built-up flexible materials which includes the attaching of the adjacent extending marginal portions of each side wall or section of the luggage, of which there are two, in its build-up.

Another object is to provide an improved stiffener or frame structure for hand carried luggage which is built-up step-by-step, and slide fastener means for the luggage or bag sections.

Other objects and advantages will appear as this description progresses and by reference to the drawing in which:

Figure 1 is a longitudinal sectional elevation taken through a form with a base strip temporarily secured thereto, showing a first step in carrying out this improved method.

Figure 2 is an enlarged fragmentary transverse sectional elevation approximately on the line 2—2 of Fig. 1.

Figure 3 is an enlarged fragmentary transverse sectional elevation showing a second step of the method.

Figure 4 is an enlarged transverse sectional elevation showing a further step in carrying out the method.

Figure 5 is an enlarged fragmentary transverse sectional elevation showing an additional step of the method.

Figure 6 is an enlarged plan elevation of the luggage or bag after the improved method has been practiced thereon.

Figure 7 is an enlarged transverse sectional elevation taken approximately on the line 7—7 of Fig. 6.

Referring by numerals to the accompanying drawing 8 designates a form constructed of a shape to represent a hand carried luggage bag such as shown at 9 in Fig. 7 having opposing

opening sections 10, each of said sections at their lower ends being connected to a base structure 11 and at their meeting edges being secured by slide fastening means or zippers 12.

5 In carrying out the method for constructing the luggage frame work, a relatively wide and long strip 13 of flexible material such as leather is secured by tacking 14 or the like over the form 8 in the manner shown in Fig. 1 with its ends 15 extending under and engaging the bottom surface 16 of the form, said strip 13 when secured to the form assuming the longitudinal shape of the required frame work to be made into the shape of the luggage or bag.

10 15 The next or second step of this improved method is to engage and mount the side walls or sections 10 over the walls 17 of the form 8 with their inner marginal portions 18 engaged over the base strip 13 adjacent its side edges as shown in Fig. 20 3 and in this position the marginal portions 18 of the bag side walls are secured to the base strip by the application of rubber cement or the like.

25 The third step in carrying out the method is to provide a pair of relatively narrow flexible strips 19 of the approximate length of the base strip 13 and to secure to each strip by cementing to adjacent under sides thereof, the co-operating sections 20 of the slide fasteners 12 in the manner shown in Fig. 4.

30 The next or fourth step is to mount the strips 19 with the slide fasteners 12 secured thereto, on and over the base strip 13, centrally thereof, said pair of strips 19 and the fabric portions 21 of the co-operating parts 20 of the fasteners 12, 35 being cemented over the marginal portions 18 of the bag walls 10 in the manner as shown in Fig. 5.

40 In constructing luggage frame work of this character a pair of slide fasteners 12 are used in the manner as shown in my accompanying application Ser. No. 550,103, filed Aug. 18, 1944, with the opening ends of the fasteners meeting intermediate the longitudinal length of the bag with the slide lugs 22 adjacent each other on the top of the bag or luggage as shown in dotted lines in Fig. 6.

45 When securing the fasteners 12 to adjacent portions, of the pair of strips 19, it is preferable to do so while the fasteners are in closed formation, and after the cemented together parts have become set, the slide lugs 22 of the fasteners 12 are slid thereon to full open positions at the ends 50 55 15 of the base strip 13. The base strip 13 is then longitudinally split or cut by a sharp instrument the entire length thereof on the line 23 form-

ing a pair of frame sections 24, as shown in Fig. 6 and the tacking 14 is removed from the base strip and the form 8. In the event headless tacks are used for securing the base strip 13 to the form 8 each section 24 of the frame work may be pulled from the tacking 14 and the tacking subsequently pulled from the form.

For further securing the parts of the frame work sections 24 together after their removal from the form 8, stitching 25 is made longitudinally on each strip 19, said stitching passing through the fabric portions 21 of each co-operating part 20 of the respective fasteners 12 and respective severed parts of the base strip 13. Other longitudinal stitching 26 is made through each strip 19, the marginal portion 18 of respective walls or sections 10 and through respective severed parts of the base strip 13.

The afore described method relating to the preforming of the parts 13, marginal portions 18 of respective parts or sections 10, fasteners 12, the two pair of strips 19 and subsequent longitudinal stitching to the base strip 13, provides the frame section 24 for each bag section 10 and which frame sections 24 when secured to each other by the slide fasteners 12, provides a frame structure for hand carried luggage and bags which is sufficiently strong and durable for retaining its preformed shape during carrying use of the bag.

While it has been described in detail that the co-operating parts 20 of each fastener 12 are secured to respective strips 19 before said co-operating parts and strips are mounted and secured to the marginal portions 18 and the base strip 13, it is nevertheless possible to first secure each of the co-operating parts 20 of the fasteners 12 to the marginal portions 18 or the base strip 13 and afterwards secure the strips 19 to the base strip and the marginal portions 18 of the bag sections 10.

After each bag section 10 has been provided with this improved frame section 24, the base structure 11 may then be formed and secured to the said sections.

During longitudinal splitting or cutting of the base strip 13 with the built-up parts thereon, before its removal from the form 8, care must be taken to prevent cutting or separating of respective ends of the fasteners 12.

While I have described one embodiment of my invention with some particularity, obviously many other embodiments thereof may occur to those skilled in the art to which it appertains. I, therefore, do not limit myself to the precise details described, but claim as my invention all variations and modifications coming within the scope of the subjoined claims.

What I claim is:

1. The method of making a luggage frame consisting of providing a form of a required shape, of temporarily securing a base strip of flexible material to the form, of securing marginal portions of a pair of opposed bag sections to said base strip, of securing a pair of longitudinally aligned slide fasteners to said base strip, and of securing respective flexible strips over portions of said fasteners and said marginal portions of said bag sections.
2. The method of making a luggage frame consisting of providing a form of a required shape, of temporarily securing a base strip of flexible material to the form, of securing marginal portions of a pair of opposed bag sections to said base strip, of securing a pair of longitudinally aligned slide fasteners to the said strip, of securing respective flexible strips over portions of said fasteners and said marginal portions of said bag sections, and of longitudinally separating the base strip.
3. The method of making a luggage frame consisting of providing a form of a required shape, of temporarily securing a base strip of flexible material to the form, of securing marginal portions of a pair of opposed bag sections to said base strip, of securing a pair of longitudinally aligned fasteners to the base strip and/or said bag sections, of securing respective flexible strips over portions of said fasteners and said bag sections, and of longitudinally separating the base strip.
4. The method of making a luggage frame consisting of providing a form of a required shape, of temporarily securing a base strip of flexible material to the form, of securing marginal portions of a pair of opposed bag sections to said base strip, of securing a pair of longitudinally aligned fasteners to the base strip and/or said marginal portions of said bag sections, of securing respective flexible strips over portions of said fasteners and said bag sections, of longitudinally separating the base strip, and of further securing the parts on each longitudinally separated section of the base strip by stitching or the like.
5. The method of making a luggage frame consisting of providing a form of a required shape, of temporarily securing a base strip of flexible material to the form, of cementing marginal portions of a pair of opposed bag sections to said base strip, of cementing a pair of longitudinally aligned slide fasteners to said base strip, of cementing respective flexible strips over portions of said fasteners and said marginal portions of said bag sections, and of longitudinally separating the base strip.

JOHN RIESS.
